(57) **CLAIM**

The ornamental design for a pocket configuration for luggage, bags, backpacks and the like, as shown and described.

DESCRIPTION

FIG. 1 is a front view of a pocket configuration for luggage, bags, backpacks and the like showing my new design; and, FIG. 2 is a perspective view thereof.

The broken lines depict the claim boundary and form no part of the claimed design. The claimed design is indicated by the relatively dark portions in the figures found within the broken lines. The relatively light portions outside the broken lines form no part of the claimed design.

1 Claim, 2 Drawing Sheets
